UNITED STATES PATENT OFFICE.

OLIVER R. JONES, OF WELAND, ONTARIO, CANADA.

WRENCH.

1,352,136.

Specification of Letters Patent. Patented Sept. 7, 1920.

Application filed August 11, 1919. Serial No. 316,769.

To all whom it may concern:

Be it known that I, OLIVER R. JONES, a subject of the King of Great Britain, residing at Welland, in the county of Welland and Province of Ontario, Canada, have invented certain new and useful Improvements in Wrenches, of which the following is a specification.

My invention relates to improvements in wrenches, and consists essentially of a handle having means for permitting the jaws to slide longitudinally thereupon.

The object of the invention is to provide a wrench which will, to a considerable extent, enable the user to complete an entire revolution in the rotation of an object engaged therewith, without relieving or loosening the grip, in positions where adjacent obstructions would ordinarily interfere with the movement of the handle of an ordinary wrench.

A further object is to provide a wrench of the class specified which may be, if desired, adjusted so that the jaws are rigid with the handle.

A still further object is to provide such a device which will be simple, durable, efficient in operation, and inexpensive to manufacture.

These, together with other objects, may be obtained by the construction, combination and arrangement of the parts as will be hereinafter more fully described, illustrated in the accompanying drawing, and pointed out in the claim hereunto appended.

Reference may now be had to the accompanying drawing, in which:

Figure 1 is a side view of the improved wrench; and,

Fig. 2 is an end view of the same.

Similar reference characters refer to similar parts throughout the two views.

Primarily, it is particularly desired to point out that, although the wrench illustrated in the drawing is an "alligator" or pipe type, the present invention, herein-

after to be set forth, may be applied to any type of wrench regardless of its nature, or of the nature of its jaws, which may be fixed or adjustable, the wrench shown in the drawing being chosen only by way of example.

The smooth and serrated jaws of the wrench are indicated respectively by A and B. These parts as shown are integral. C designates the handle, which is provided with lateral opposed longitudinal grooves 2. The body portion of the jaws A, B, is longitudinally slotted as indicated by 3, and is provided with flanges 4 which fit the grooves 2 in the handle and are slidable therein.

Thus it will be seen that in rotating an object, should the handle C come in contact with an obstruction, the handle may slide along the jaws until it misses the same, when rotation may be resumed.

Stops 5 are provided at each end of the handle C for the purpose of limiting the movement of the jaws, and for preventing the same from sliding off the handle.

In the event of it being desired to procure rigidity between the jaws and their handle, a set screw 6 is threaded through the body portion of the jaws, with contact against the handle.

Having now fully described my invention, what I claim and desire to secure by Letters Patent of the United States, is:—

In a device of the class described, comprising a bar handle member regular in cross-section from end to end, a jaw-carrying member slidable on said handle from one extreme end to the other to a position when at said ends the edge of said jaw-carrying member is flush with the corresponding end of said bar handle, substantially as and for the purpose set forth.

In testimony whereof I have affixed my signature in the presence of two witnesses.

OLIVER R. JONES.
